Inventor:

Carl Arnold

By John H. Farthing
Attorney

UNITED STATES PATENT OFFICE.

CARL ARNOLD, OF NUERMBERG, GERMANY.

SPARK TOY.

Application filed March 15, 1928, Serial No. 261,932, and in Germany December 6, 1927.

Spark toys have become known in which by a depression of a rack the spark producing mechanism and a disk having several transparencies are rapidly rotated. The disk with the transparencies is slowly rotated by the centrifugal force of the rotating spark mechanism so that at certain intervals of time differently coloured sparks and in accordance therewith changing pictures become visible on the surface of the toy.

According to the invention a second disk having apertures and figurative representations is arranged above the spark producing mechanism and the colour transparent-disk is loosely mounted on the shaft of the driving mechanism and casing in such a manner, that the spark produced by the spark producing mechanism and coloured by the transparencies become visible in different colours through the apertures. The disk is loosely mounted with a slot on the axle of the driving mechanism so that, when this driving mechanism is functioning said disk is slightly shifted and shaken so that the picture on the disk, for instance a face, looks as if it was animated.

An embodiment of the invention is illustrated, by way of example, in the accompanying drawing in which:

Fig. 1 is a side elevation.

Fig. 2 is a top plan view.

The driving mechanism *a* mounted in a casing is operated, in a manner known per se, by a rack *b*. On the vertical shaft *c* of the driving mechanism a spark producing device *f* and a disk *g* with coloured transparencies are mounted.

According to the invention another disk *h*

is loosely mounted on the shaft *c* above the disk *g* with transparencies, said disk *h* having a downwardly bent arm *i* engaging with a slot *k* of the top plate of the casing to secure said disk *h* against rotation. On the upper surface of disk *h* any design can be painted, for instance a face as shown in Fig. 2. In this disk *h* apertures *l* are arranged through which the changing coloured sparks are visible. Owing to the slit *m* in the disk *h* engaging over the vertical shaft *c* the disk *h* is moved to and fro and shaken when the shaft *c* is rotating, so that the picture on the upper surface of disk *h* looks as if it were animated.

I claim:

A spark toy, comprising in combination with the spark producing mechanism mounted on a vertical shaft driven from a rack-operated driving mechanism and with a disk rotatably mounted on said vertical shaft above said spark producing mechanism and having apertures with coloured transparencies, a second disk above said disk with transparencies loosely mounted on said shaft by means of a slot said loose disk having for instance a face painted on its upper surface and several apertures in the same, and means for securing said loose disk against rotation but permitting shifting movements of the same so that, when said vertical shaft is rotating, said upper disk is moved to and fro and shaken so that it looks as if the face painted on its upper surface was animated the coloured sparks becoming visible through the apertures in said loose disk.

In testimony whereof I affix my signature.

CARL ARNOLD.
